UNITED STATES PATENT OFFICE.

JOHN N. DERSCHUG, OF SYRACUSE, NEW YORK, ASSIGNOR TO SYRACUSE WASHING MACHINE CORPORATION, OF SYRACUSE, NEW YORK, A CORPORATION OF NEW YORK.

CLOTHES WRINGER.

Application filed March 24, 1920. Serial No. 368,253.

To all whom it may concern:

Be it known that JOHN N. DERSCHUG, of Syracuse, in the county of Onondaga, in the State of New York, has invented new and useful Improvements in Clothes Wringers, of which the following, taken in connection with the accompanying drawings, is a full, clear, and exact description.

This invention relates to certain improvements in clothes wringers in which the wringer rolls are mounted in a metallic frame for relative radial as well as rotary movement, and are yieldingly held in their pressing positions by a leaf spring, which is adjustable at will to vary the degree of pressure, in combination with a water board which is slidable transversely of and below the rollers, and tiltable in reverse directions to guide the clothes as they are fed between and by the wringer rolls in reverse directions.

The main object is to increase the general working efficiency, strength and durability of machines of this character, and, at the same time, to reduce the cost of manufacture.

Another object is to provide efficient and easily accessible means, operable at will, for instantly releasing the tension of the spring after it has been adjusted to produce any desired pressure of the rolls upon the work.

Other objects and uses relating to specific parts of the wringer will be brought out in the following descriptions:

In the drawings:

Figures —1— and —2— are, respectively, a top plan and front elevation of the wringer embodying the various features of my invention, a portion of the water board being broken away in Figure —1—.

Figure —3— is a longitudinal vertical sectional view taken on line 3—3, Figure —1—.

Figure —4— is a transverse vertical sectional view on reduced scale taken on line 4—4, Figure —2—.

Figure —5— is a detailed sectional view through one side of the wringer frame, taken on line 5—5, Figure 2.

Figures —6— and —7— are enlarged detailed sectional views through one side of the water board taken, respectively, on lines 6—6 and 7—7, Figure —1—.

As illustrated, this wringer comprises a main supporting frame —1— having a sub-

stantially central lengthwise opening —2— therethrough from front to rear, forming lower and upper bars —3— and —4— and opposite end bars —5— and —6—, said frame being divided vertically at —7— 60 through its longitudinal center to form opposite similar half sections which are preferably made of cast metal and subsequently bolted together face to face by clamping bolts —8—. 65

The object in making the frame in sections is to not only facilitate casting and assembling in that the guide openings and recesses for the movable parts may be cast in the frame without extensive coring, but 70 reduces to a minimum the amount of machine work necessary for receiving those parts, thereby greatly reducing the cost of production and increasing the output.

The lower bar —3— is provided with a 75 vertical opening —9— therethrough from top to bottom and is provided with oppositely projecting downwardly inclined flanges —10— along the upper edge of its front and rear sides to partially guide the 80 clothes, in their passage through the rollers in reverse directions, and to prevent, as far as possible, the winding of said clothes upon the lower roll.

The upright end bars —5— are provided 85 in their inner sides with channels —11— merging at their upper ends with the adjacent ends of a similar channel —12— in the lower side of the upper bar —4— for reducing the weight of the castings and for 90 other purposes hereinafter described.

A pair of rubber covered wringer rolls —13— and —14— are mounted in parallel relation within and upon the main supporting frame to extend lengthwise across the 95 opening —2—, the lower roller being provided with opposite end journals —15— supported upon bearing blocks —16— of oil saturated wood or other equivalent material, the upper roll being provided with 100 end journals —17— which are engaged by bearing blocks —18— similar to the block —16— except that they are arranged in reverse order. The journals —15— and —16— and relatively smaller portions of 105 the adjacent ends of the rollers —13— and —14— extend into the channels —11— of the corresponding upright end bars —5— and —6— so that the front and rear walls of said upright bars extend inwardly 110

slightly beyond the adjacent ends of the enlarged portions of the rollers to form guards or shields —19— which deflect the clothes from the ends toward the center, and prevent them from coming in contact with the journal bearings —16— and —18— and also from wedging between the ends of the rollers and inner edges of the upright walls —5— and —6—.

10 The bearing blocks —16— and —18— are movable vertically in the channels —11— of the upright bars —5— and —6—, the outer end walls of the opposite sections of the end bar —5— being closed across the adjacent ends of the journals —15— and —17— and bearings —16— and —18—, while the outer end walls of opposite sections of the upright bar —6— are slotted vertically along their meeting edges to receive the adjacent bearings —15— and —17— and permit vertical movement of the rollers.

15 The bearings —16— normally rest upon suitable seats —20— at the lower ends of the channels —11— for the purpose of normally holding the lower roll —13— in a horizontal plane.

20 The upper roller —14— is free to move vertically, but is normally yieldingly held in engagement with the lower roller —13— by means of a semi-elliptic leaf spring —21— which is movable in the channel —12— of the upper bar —4—, and has its opposite ends engaged with the upper faces 25 of the bearings —18—, suitable means being provided for tensioning and releasing the spring at will.

25 As illustrated, this tensioning and releasing means comprises cooperative levers —22— and —23— and an adjusting screw —24—, said levers being pivoted, respectively, at —25— and —26— to and between the front and rear walls of the channel —12— of the upper bar —4— at opposite 30 sides of the screw —24—, which is engaged in a threaded aperture —27— in the lever —22— and has its lower end engaged with the intermediate portion of a leaf spring —21—, and its upper end provided with a handle —28— by which it may be turned for varying the tension of the spring upon the bearings —18—, and thereby producing a corresponding variation of pressure 35 between the rollers.

40 These levers are movable in an opening —29— in the upper wall of the channel —12—, and, when adjusted to produce the desired tension upon the spring —21—, their upper faces lie substantially coincident with the upper face of said top wall, while the screw projects a sufficient distance above said wall to permit it to be easily operated by the handle —28—.

45 The adjacent ends of the levers —22— and —23— are recessed at —30— and

—31—, respectively, to form shoulders —32— and —33— which are arranged so that the shoulder —33— projects into the recess —30— and normally overlaps upon and engages the upper face of the shoulder —32—, the last named shoulder being normally extended into the recess —31—, and therefore directly under the shoulder —33—.

50 The overlapping or engaging portions of the shoulders —32— and —33— lie directly over the pivot —26— so that the upward pressure of the shoulder —32— against the underside of the shoulder —33— as produced by the tension of the spring —21— is in a direct line nearly parallel with the axis of the screw, or in the direction of pressure of the central portion of the spring, thereby establishing a frictional lock between the meeting faces of said shoulders to hold both levers in their adjusted positions without extra locking means.

55 The lever —23— extends from its shoulder —33— some distance beyond the opposite side of the pivot —26— where it is provided with a hand piece —34— projecting a short distance above the top of the bar —4— to permit it to be engaged by the hand for depressing said lever to the position shown by dotted lines, and thereby releasing the lever —22— and the tension of the spring —21—, which also releases the pressure of the rolls one upon the other.

60 When readjusting the tension of the spring, the screw —24— may be turned upwardly a sufficient distance to allow the levers —22— and —23— to be again interlocked with each other, whereupon, the screw may be adjusted to produce a desired tension upon the spring and corresponding pressure between the rollers.

65 The front and rear walls of the channeled bar preferably extend downwardly a sufficient distance to cover the edges of the spring —21—, and serve as guard shields to reduce the liability or danger of injury to the hands of the operator by being caught between the spring and lower edges of the bar —4— when the spring is released.

70 The side bars —5— and —6— extend downwardly some distance below the lower lengthwise bar —3— to form supporting guides —35— for a transversely movable water board or table —37—, which consists, in this instance, of a pair of similar side rails —38—, a sheet metal plate —39— secured to the side rails and holding them in fixed spaced relation, and front and rear rollers —40— journaled at their ends upon the ends of the side rails —38—.

75 The marginal edges of the sheet metal plate —39— are preferably bent downward at —41— for reenforcing purposes, the opposite sides of said plate being seated in recesses —42— in the inner faces of the side rails —38— and are firmly held in this position.

sition by screws —43— and clamping bars —44—, which latter engage the inner faces of the adjacent downturned edges of the plate —39— and are provided with threaded apertures for receiving the screws —43—.

The side rails —38— are provided with lengthwise slots —45— for receiving guide pins —46—, which are mounted upon the extensions —35—, one of said pins consisting of a screw which may be removed to permit the water board to be removed and replaced at will.

The slots —45— in the side rails —38— extend throughout the greater portion of the length of said rails to permit the water board to be adjusted transversely of and under the rollers —13— and —14— and tilted rearwardly or forwardly as it is moved to corresponding extreme positions, or it may be locked in certain positions by means of a locking bolt —47—, which is movable in one of the extensions, as —35—, against the action of a spring —48—, and is adapted to engage in one of a series of apertures —49— in the adjacent rail —38—.

The purpose of the water board is to support and guide the clothes some distance beyond the rollers in transit therethrough in either direction, or may be used to catch the drip of water from the rolls and deflect it back into the washing vat, particularly, when the wringer is used in connection with a washing machine as shown in my pending application, Ser. No. 355,515, filed Jan. 31, 1920.

In the operation of the spring releasing mechanism, assuming that the levers —22— and —23— are interlocked with each other, and that the spring is placed under tension by the adjustment of the screw —24—, then, if desired to instantly release the pressure upon the rollers, as for example in case of accident or the accumulation of an excessive thickness of clothing between said rollers, it is simply necessary to press downwardly upon the hand piece —34—, which disengages the lever —23— from the lever —22—, thereby releasing the spring, which, by its distension throws the lever —22— and its screw —24— to the position shown by dotted lines, thereby releasing the pressure upon the rollers.

What I claim is:

1. In a wringer of the character described, the combination of a frame having an upper lengthwise bar and upright end bars, the upper bar having a lengthwise channel in its lower side, bearings movable vertically in the upright end bars, lower and upper rollers journaled in said bearings, an upwardly arched leaf spring extending lengthwise of and within the channel and having its ends engaged with the bearings for the upper roller, a lever pivoted to the upper

bar to swing vertically toward and from the spring and provided with a threaded aperture, means operable at will into and out of engagement with the lever for locking and releasing the same, and a screw engaged in the threaded aperture of said lever for adjusting the tension of the spring.

2. In a wringer of the character described, the combination of a frame having an upper lengthwise bar and opposite upright end bars, said upper bar having a lengthwise channel in its lower side, journal bearings in the end bars, lower and upper rollers having their ends journaled in said bearings, the bearings for the upper roller being movable vertically, an upwardly arched leaf spring extending lengthwise of said channel and having its ends engaged with the bearings for the upper roller, a lever pivoted to the upper frame bar to swing vertically toward and from the spring and provided with a threaded opening, a screw engaged in said opening for engaging the central portion of the spring and tensioning the same, and a detent pivoted to the upper bar to swing about a horizontal axis into and out of holding engagement with said lever.

3. In a wringer, the combination of a frame, journal bearings mounted on opposite ends of the frame, rollers journaled in said bearings one above the other, an upwardly arched bow-spring having its ends engaged with the upper bearings, a lever pivoted to the frame above the spring to swing toward and from said spring, a screw mounted on and movable with said lever toward and from the spring, and a detent pivoted to the frame to swing about a horizontal axis into and out of engagement with the lever, said lever and detent engaging each other in substantially the same vertical plane as and above the pivot of the detent.

4. In combination in a device of the class described, a pair of pressure rolls, means for supporting one of said rolls for movement toward and from the other, a bow spring for maintaining said movable roll normally in contact with the other roll, an adjustable screw normally engaging the middle portion of said spring, a pivoted member having a threaded opening for engagement by said screw and a latch tooth adjacent its free extremity, a pivoted latch for engagement with said tooth and a manually depressible member for disengaging said latch from the tooth.

In witness whereof I have hereunto set my hand this 18th day of March 1920.

JOHN N. DERSCHUG.

Witnesses:

H. E. CHASE,
ROSE G. CARROLL.
